J. L. KIMBALL

FLUID PRESSURE GOVERNOR

Filed Oct. 19, 1925

INVENTOR.

James L. Kimball

UNITED STATES PATENT OFFICE.

JAMES LEWIS KIMBALL, OF SALEM, MASSACHUSETTS, ASSIGNOR TO RUGGLES-KLINGE-MANN MFG. CO., OF SALEM, MASSACHUSETTS.

FLUID-PRESSURE GOVERNOR.

Application filed October 19, 1925. Serial No. 63,335.

This invention relates principally to an improved valve structure and it particularly relates to a valve structure adapted for the controlling of fluid pressure.

5 The principal object of my invention is to provide a valve of the class described in which the reaction effect due to the velocity flow is prevented from disturbing the normal biased relation between the valve and 10 its actuating means.

Another object is to provide a valve in which the internal parts including the seat ring are held in place by the bonnet or cover bolting and are therefore easily removed for 15 inspection, repairs or renewal when the bonnet or cover is removed.

A further object is to provide a predetermined loss motion between the valve and the valve-actuating means whereby the valve 20 will be opened at a predetermined pressure but will not close until a predetermined higher pressure is reached.

A regulating valve such as I have disclosed has a general application in the control of 25 fluid pressure; they can be used as a reducing pressure regulator or as a pump governor for regulating the speed of the pump to control the discharge pressure.

It is desirable that such valve be pressure 30 tight when closed, otherwise, the pressure in the system may be increased over the pressure setting of the regulator. For this reason we prefer to use a single seated valve of the pilot operated type. It is a well known 35 fact, however, that this type of valve while balanced to fluid pressure has not heretofore been so constructed as to maintain a balance under varying degrees of velocity flow. My invention provides means whereby the im- 40 pulse and reaction effect of the velocity flow is equalized in such a way that the valve maintains its balance for all degrees of opening except for a slight tendency toward closing which has been found desirable.

45 It is also desirable when such valves are used for the control of pumps not to operate such pumps continuously but to start the pump at a predetermined low pressure and to stop the pump at a predetermined higher 50 pressure; especially is this desirable when

controlling fire pumps for maintaining pressure on sprinkler systems where the normal demand is only the leak of the system. It is more preferable to have periodical pumping periods than it is to have a large pump capable of supplying a fire demand operating continuously on a demand due only to the leak of the system. 55

It will also be noted that I have devised a novel valve structure in which all internal 60 parts are easily removed without the use of tools after the bonnet or cover is removed. These and other improvements are fully set forth in the following specifications and pointed out in the annexed claims. 65

In the accompanying drawing forming a part of this specification is illustrated a sectional vertical elevation of my invention. A valve casing (1) has inlet (2) and outlet (3), a dividing wall (4) separates the inlet 70 from the outlet, a seat ring (5) is held in position in the dividing wall by valve cage (6) and valve cage (6) is in turn held in position by valve bonnet (7). A valve (8) is arranged to engage valve seat (5) to check 75 the flow of fluid pressure from the inlet to the outlet of the valve casing (1). Valve (8) has a cylindrical extension (9) which is loosely fitted to the cylindrical valve cage (6) and permitting fluid pressure from the 80 inlet of the valve casing to enter and fill chamber (10). The only outlet from this chamber (10) is by orifice (11) in the center of the valve (8) and this orifice is controlled by pilot valve (12). This pilot valve 85 (12) is in a chamber (13) formed in the cylindrical extension (9) of valve (8). Fluid pressure is permitted to freely flow from chamber (10) to chamber (13) through ports (14). It will be understood that when the 90 pilot valve (12) is lifted it first uncovers orifice (11) which allows the pressure in chamber (10) and (13) to be dissipated to a value corresponding to the pressure at the outlet (3) of the valve casing (1). This 95 balances the valve (8) to pressure; for the reason that there will be the same pressure above as below the valve (8) and as the bore of the valve ring (5) is the same diameter as the bore of the valve cage (6) the lifting 100

of the pilot valve balances the main valve (8). A farther lift of the pilot valve (12) engages guide nut (15) which is secured in the upper end of the cylindrical extension 5 (9) and the main valve (8) is lifted from its seat allowing fluid pressure to flow from the inlet of the valve through ports (16) thence through the lower end of ports (17) and port (18).

10 It will be seen that the main valve (8) has both an upward and a downward extension. It will be understood from the foregoing description that the purpose of the upward extension is to balance the pressure on the 15 valve. The purpose of the downward extension is to balance the valve to velocity flow of the fluid passing from the inlet to the outlet. This is effected by forming a flange (19) at the lower end of the slotted 20 cylindrical extension. If there was no bottom flange (19) the flow of fluid pressure would be directly against the bottom of the casing (1) and the impulse of the flow would react against the valve disc (8) causing it 25 to be thrown out of balance and tend to be forced to an open position. This unbalancing of the valve (8) due to velocity flow would have a very disastrous effect in attempting to secure close regulation of the 30 pressure. By forming flange (19) at the bottom of the cylindrical extension (20) I provide means whereby a part of the impulse effect is against this flange, and by means of the port (18) a part of the impulse effect 35 is against the valve casing (1). By properly proportioning the size of port to the total area of the flange the impulse effect tending to close the valve can be made to exactly balance the reaction effect tending 40 to open the valve and thereby the valve becomes closely balanced to pressure and velocity flow.

A further object of this improved valve structure is to provide means for holding the 45 valve seat in position so it can be easily removed when the valve bonnet (7) is removed. This is accomplished by making the balancing cylinder (6) the proper length to engage the above ring (5) and to come flush 50 with the top of the valve casing so that a gasket or packing placed between the flanges of the valve casing and valve bonnet will form a tight joint covering not only the bonnet and valve flange but the top flange of 55 the cylinder (6). It will be seen that in this way that both the balancing cylinder and valve seat ring are held in place by the bolting of the bonnet to the valve body, and when the bonnet is removed all internal parts 60 are easily removable.

In the operation of this valve from pressure variation I have arranged a novel pressure motor comprising of a diaphragm (21), diaphragm pressure chamber (22), diaphragm cap (23), pressure cap (24), pressure

head (25) and actuating lever (27). Actuating lever (27) is fulcrumed at point (28), and the pressure on the diaphragm (21) is transmitted to lever (27) by toggle points (29) which are in contact with toggle pin (30). This pressure is counteracted by spring (31) which is connected to the lever (27) at point (32) by means of adjusting rod (33). The opposite end of the lever is connected with valve stem (34) by means of a loss motion, the purpose of which will be hereafter explained. The pressure to be regulated or controlled by the valve is connected to diaphragm plate (23) at (35).

When used as a fluid pressure pump 80 governor the discharge pressure of the pump is connected at (35), and the valve is installed in the steam supply to the pump; in this way the speed of the pump is governed to maintain a uniform predetermined discharge pressure. When used as a reducing pressure valve the reduced pressure, or the pressure at the outlet of the valve (8) is connected at (35). Variations in pressure acting on the diaphragm open and close valve 85 (8) to maintain the desired pressure in the system. On a reduction in pressure below a predetermined mean average value the spring (31) overcomes the pressure on the diaphragm (21) and the valve spindle (34) 90 is raised, first opening pilot valve (12) and exhausting the pressure in chamber (10) through port (11) to the outlet of the valve after which the main valve (8) is lifted without resistance of the steam pressure or 95 velocity flow. An increase in pressure above the predetermined mean average value will force diaphragm (21) downward compressing spring (31) and closing off both the pilot valve (12) and main disc (8).

Oftentimes in the control of pumps it is desirable in order not to operate the pump continuously to pump up a certain predetermined pressure and then close down the pump allowing the pressure to fall off say 100 ten or fifteen pounds before again starting the pump.

To accomplish this purpose, I provide certain loss motion between the lever (27) and the valve stem (34). This is effected by elongating the hole in the lever connection, making the connecting pin (37) a close fit in the lever (27) but allowing a certain movement before the pin engages the lever connection (36) to move the valve stem (34). By varying the amount of loss motion between these two members, any amount of pressure variation between the starting and stopping of the pump can be effected.

One of the novel features of this valve is that the diaphragm has a relatively small travel in relation to the travel of the valve, and likewise the spring has a still further reduced travel in relation to the diaphragm movement. This arrangement of parts pre- 125

vents excessive straining of the diaphragm rubber and its re-inforced fabric and prolongs the life of the diaphragm.

By effecting a relatively small travel of the spring in relation to the valve, the valve is entirely opened or closed on a less variation in pressure than would be the case where a greater movement of the spring were required. The function and operation of the improved governor above described is made clear by the following description: An increase in pressure acting on the diaphragm first moves the operating lever to take up the loss motion between the operating lever and the valve spindle after which the spindle is moved to close the main valve, the pilot valve remaining open until the main valve reaches its seat, after which the pilot valve is closed. In opening on a reduction in pressure the loss motion is first taken up and then the pilot valve opens and exhausts the pressure from chamber 10 which places the main valve in a balanced condition as to pressure and then the main valve can be freely lifted from its seat.

It will be understood that the taking up of the loss motion between the operating lever and the valve spindle plus the loss motion necessary to open the pilot valve causes a certain drop in pressure on the diaphragm and this causes the governor to act at a predetermined low pressure; likewise in closing these loss motions must be overcome which retards the closing of the valve and causes it to remain open until a predetermined high pressure is reached.

It will be understood that after the main and auxiliary valves have been closed the inlet pressure at (2) enters and fills chamber (10) by passing between the valve extension (9) and the bore of the valve cage (6), these parts being loosely fitted to allow for the passage of fluid pressure and to prevent sticking but not sufficiently loose to allow more steam to enter chamber (1) than can be exhausted through pilot valve orifice (11).

I am aware of the fact that single seated main valves with a pilot valve for balancing the pressure on the main valve are old in the art, but, so far as I am aware, the method herein disclosed of holding the seat ring in place by the balancing cylinder or valve cage is new. Such valves as heretofore constructed were not suited for use in connection with a diaphragm pressure responsive device for the reason that the main valve was not balanced to velocity flow and therefore the main valve would kick open due to impulse and reaction effect. In my invention, the main valve is steadied by the velocity flow acting on the inwardly extended flange (19) and this improvement is within the scope of my invention.

Having thus described the nature of my

invention and set forth a construction embodying the same, what I claim as new and desire to secure by Letters Patent of the United States is:—

1. In a fluid pressure governor comprising a valve casing having an inlet and an outlet for the passage of fluid pressure, a main valve in said casing adapted to control the flow of fluid pressure from the inlet to the outlet, a cover for said valve casing, a valve ring in said casing adapted to be engaged by said main valve when closed, an upward cylindrical valve cage adapted to hold said valve ring in position by the bolting of the valve cover and to act as a balancing chamber for the main valve, a pilot valve arranged to balance the pressure on the main valve, a valve stem connected to the pilot valve, the main valve being constructed with a downward cylindrical extension having circumferential ports for the passage of fluid pressure and a bottom inwardly extending flange adapted to receive an impulse from the velocity flow of the fluid pressure and thereby exert a force tending to maintain the pilot valve in an open position for all positions of opening of the main valve, and a pressure responsive device for controlling the pilot valve.

2. In a fluid pressure governor comprising a valve casing having an inlet and an outlet, a main valve in said casing adapted to control the flow of fluid pressure from the inlet to the outlet, a cover for said valve casing, a valve ring in said casing adapted to engage said valve when closed, an upward cylindrical valve cage adapted to hold the valve ring in position by the bolting of the valve cover and act as a balancing chamber for the main valve, a pilot valve for balancing the pressure on the main valve, a valve stem connecting with the pilot valve, a pressure responsive device positioned vertically eccentric to the valve stem, an operating lever in engagement with the pressure responsive device and arranged to be operated thereby, a pressure counteracting spring connected to one end of said lever, said lever being fulcrumed between said spring and the pressure responsive device, the opposite end of the lever being connected to the valve stem, said connection having a loss motion permitting the valve to open at a predetermined low pressure and continue open until a predetermined higher pressure is reached.

3. In a fluid pressure governor comprising a valve casing formed with an inlet chamber and an outlet chamber, a cover for said valve casing, a main valve controlling communication between said two chambers, a valve seat ring arranged to be engaged by the main valve when in a closed position, an upward cylindrical valve cage arranged to hold said valve seat ring in position by the bolting of the valve cover and to act as a balancing

chamber for said main valve, a pilot valve arranged to balance the pressure on the main valve, a valve stem connecting with the pilot valve and extending through a stuffing box in the valve cover, a pressure responsive device positioned vertically eccentric to the valve stem, an operating lever in engagement with the pressure responsive device and arranged to be operated thereby, a pressure counter-

acting spring connected to one end of said lever, said lever being fulcrumed between said spring and the pressure responsive device, the opposite end of the lever being connected to the valve stem, whereby variations in pressure acting on the pressure responsive device operate the pilot valve to control the operation of the main valve. 10 15

JAMES LEWIS KIMBALL.
